described.**DESCRIPTION**FIG. 1 is a perspective view of a tire tread showing our new
tire tread design, it being understood that the tread pattern is
repeated uniformly throughout the circumference of the tire
tread with the opposite side being the same as for the side
shown; and,FIG. 2 is an enlarged fragmentary front elevation view
thereof.The broken line showing of a tire sidewall and inner bead is
for illustrative purposes only and forms no part of the
claimed design.**1 Claim, 2 Drawing Sheets***Fig. 1*
